A. J. LIBERTY,
DETACHABLE POWER DRIVEN PROPELLER FOR BOATS,
APPLICATION FILED FEB. 10, 1919.

Patented Sept. 16, 1919

UNITED STATES PATENT OFFICE.

ANTOINE J. LIBERTY, OF DETROIT, MICHIGAN.

DETACHABLE POWER-DRIVEN PROPELLER FOR BOATS.

1,316,169.

Specification of Letters Patent. Patented Sept. 16, 1919.

Application filed February 10, 1919. Serial No. 276,056.

To all whom it may concern:

Be it known that I, ANTOINE J. LIBERTY, a citizen of the United States, residing at Detroit, county of Wayne, State of Michigan, have invented a certain new and useful Improvement in Detachable Power-Driven Propellers for Boats, and declare the following to be a full, clear, and exact description of the same, such as will enable others skilled in the art to which it pertains to make and use the same, reference being had to the accompanying drawings, which form a part of this specification.

My invention relates to a detachable power driven propeller for boats shown in the accompanying drawings and more particularly pointed out in the following specification and claims.

An application for patent for this invention was filed August 1, 1914, Serial No. 854,581, and allowed August 19, 1915.

It is well known that one of the main objections to a detachable outboard motor is that it cannot be used in shallow waters, or in waters in which weeds are apt to become entangled in the blades of the propeller.

When, therefore, it becomes necessary to make a landing in shallow water, the device must first be disengaged from the stern that the boat may land or be drawn up on the shore, otherwise the propeller blades are apt to be injured in forcing the boat over a shallow or rocky beach or the stern broken to which it is clamped.

One of the objects of the present invention, therefore, is to provide a detachable outboard propeller which may be clamped to the stern of any small boat, but which is adapted to be raised above or even with the surface of the water in order that the boat may make a landing on a shallow beach, or that the propeller may avoid the weeds which would otherwise become entangled in its blades.

Another object of the invention is to eliminate all bevel or other gears, usually employed in devices of this character and to otherwise simplify its construction and reduce the cost of manufacture.

Another object is to provide a platform or bed plate hinged to the clamping member, on which any suitable type of motor may be mounted and coupled directly with the propeller shaft, the construction being

such that a universal joint between the engine shaft and propeller shaft may be dispensed with together with all connecting gearing.

Other advantages and improvements will hereinafter appear.

In the drawings accompanying this specification:—

Figure 1 is a side elevation of a propeller wheel and shaft with parts broken away, clamped to the stern of a boat, a fragmentary portion of the latter being shown in section.

Fig. 2 is a plan view of the device with parts broken away.

Referring now to the letters of reference placed upon the drawings:

A, indicates a row boat or other small vessel, B its rudder and C, the tiller ropes connected with the arm mounted on the post of the rudder.

D, denotes an internal combustion engine or other motor, D', its driving shaft, and D² the fly wheel.

E, indicates a tilting platform, to which the engine or other prime mover is secured,—pivoted at e to the clamp F, by which the device is attached to the stern of a boat.

G, is a frame bolted to the platform and provided with a hub portion G', to receive a tube H, inclosing the propeller shaft I.

I' is a coupling connecting the propeller shaft I with the engine shaft D.

J is a propeller wheel secured to the outer end of the shaft I.

K denotes a spider frame having a hub portion to receive the tube H to which it is secured, provided with radiating arms, the ends of which are perforated for the passage of the truss rods L which are preferably three in number. The rear ends of the rods are engaged with a suitable casting M, mounted on the outer end of the tube H; their opposite ends being severally threaded to receive adjusting nuts h, to connect them with the tilting platform E,—through, or by means of, an arm L² and hub G' of the frame G.

N indicates an arm bolted to the underside of the platform E, by means of which the propeller wheel may be raised or lowered by rocking the platform and frame on the pivot e, journaled in the clamping member F.

P are slotted arms pivoted at P' to the

clamp F, and P² are adjustable thumb nuts, the bolts of which pass through the respective slotted arms P, engaging lugs P³, carried by the tilting platform E.

5 Having indicated the several parts by reference letters the construction and operation of the device will be readily understood.

To install the device upon a boat, its supporting frame is secured to the stern by 10 means of the clamping member F, as clearly shown in the drawings. The shaft of the propeller is then tilted downward until the latter is sufficiently submerged. It may then be secured in its adjusted position by means 15 of the thumb nuts P², or it may be left free to rise or fall as required.

In shallow water, or water infested with weeds the propeller wheel may be raised by 20 forcing down the arm N, upon loosening the thumb nuts P²,—if previously tightened,—thus avoiding striking the bottom or becoming entangled with the weeds.

While the clamping nuts P² are designed to 25 secure the propeller at a certain fixed angle, I have found it unnecessary in practice to secure the shaft in this way, as the weight of the propeller is sufficient to keep it properly submerged, the weight of the motor mounted on the tilting platform serving to 30 maintain the shaft at the proper angle. It will also be obvious that if the propeller shaft is left free to adjust itself to varying conditions it will in many cases be a distinct advantage, as for example in making a landing at an unknown shore the propeller will 35 rise as the water grows shallow and thus avoid injury to the blades in the event of striking a rocky bottom.

Having thus described my invention, 40 what I claim is:—

1. In a device of the character described, a clamping member adapted to engage the stern of a boat, a tilting frame secured

thereto, a sleeve carried by the frame adapted to inclose a propeller shaft, a propeller shaft journaled in the sleeve, means for coupling the shaft to a prime mover mounted upon the tilting frame, a propeller wheel secured to the shaft, means for manually tilting the frame and propeller shaft 45 and for securing the same when adjusted comprising a slotted arm pivoted to the clamping member, and a co-acting adjustable set screw extending through said slotted member engaging the tilting frame. 50 55

2. In a device of the character described, an adjustable clamping member adapted to engage the stern of a boat, a tilting motor supporting frame hinged to the clamping member, arms extending rearwardly from 60 the tilting frame adapted to engage and support a tubular member, a tubular member supported by said arms, a casting having radiating arms carried by the tubular member, a propeller shaft journaled in the tubular member, a propeller secured to the shaft, tension rods connected with the tubular member and the tilting frame and engaging the radiating arms of the casting carried by 65 said tubular member, means for manually raising and lowering the motor supporting frame and propeller shaft, and means for securing the motor supporting frame and propeller shaft when adjusted, comprising a slotted bar pivoted to the clamping member, and an adjustable thumb screw carried by the tilting frame projecting through said 70 slotted bar adapted to engage the latter, whereby the tilting frame may be held 75 against displacement when adjusted. 80

In testimony whereof, I sign this specification in the presence of two witnesses.

ANTOINE J. LIBERTY.
